UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

CORRUGATED STRUCTURE FOR RAILWAY CARS.

Application filed October 23, 1925. Serial No. 64,465.

My invention relates to the construction of railway cars having parts formed of metallic plates which are subjected to lateral, buckling and sometimes torsional stresses.

5 Said parts are made of one or more metallic plates or panels formed with vertical or horizontal corrugations or other integral stiffening or bracing means to resist such stresses. While efforts are made to block 10 the lading in the car, the shocks caused by the heavy locomotives, the emergency air brake and the classification hump tear the lading away from its moorings and throw it against the end of the car, the lateral weaving 15 of the car throws it against the side of the car, and the impact throws it against the bottom of the car. My invention is adaptable to several parts of a railway car, such as side doors, side walls, floor sheets (sloping or otherwise), hopper doors, roof sheets, etc., but it is especially adaptable for use as the end wall of a railway car and is also adaptable to box, gondola or other types of cars.

25 One of the objects of the invention is to provide metallic parts of a railway car which have great strength to resist the torsional and weaving stresses which exist in a railway car when moving in service. These 30 stresses are caused by the inertia of the roof and superstructure when the train is suddenly stopped; rough or uneven track; the superelevation of the track on curves; the lateral inertia in rounding curves; eccentric 35 thrust due to the lading being secured to one side of the car; the cars being "cornered"; the use of push pole pockets, etc. Such stresses rack and distort the superstructure which decreases the life of the car, and also 40 causes the car to leak grain, sand and other such material. Furthermore, such stresses cause leaky roofs and leaky and inoperative side and end doors.

The tendency of an all metal end wall to 45 bulge is resisted partially by the corrugations, stiffening members or whatever means have been provided to transmit such stresses to the side wall or frame members of the car. Such tendency is also resisted by the corner 50 post of the car acting as a vertical beam supported at its top and bottom and sustaining a horizontal load; in other words, the bulging of the end would pull the opposite corner posts toward each other. This 55 bulging also tends to pull the end (or side)

plate downwardly and the end (or side) sill upwardly. Another object of the invention is to reinforce the frame members against thrust perpendicular to their length by means forming a part of a corrugated or 60 otherwise reinforced metallic end wall.

Since the corrugated metallic wall is braced against buckling it in itself has considerable resistance to the lateral stresses but the wall must be well secured to the frame 65 members, (post, sill and plate) in order to secure the co-operation between these frame members and between the metallic wall and the frame members. Another object of the invention is to obtain an improved method 70 of securing a corrugated metallic wall to the frame members of the car.

In the drawings:

Fig. 1 shows my invention applied to a 75 wooden box car.

Fig. 2 is a side elevation of Fig. 1.

Fig. 3 is a section on line 3—3 of Fig. 1.

Fig. 4 is a section on line 4—4 of Fig. 1.

Fig. 5 shows a detail of the metallic plate.

Fig. 6 is a section on line 6—6 of Fig. 5. 80

Fig. 7 is a section on line 7—7 of Fig. 5.

Fig. 8 is a section on line 8—8 of Fig. 5.

Fig. 9 is an enlarged view of the corner 70 post of Fig. 4 and its associated parts.

Fig. 10 is a fragmentary elevation of 85 Fig. 9.

A part of the metallic plate is pressed to form a panel 14 surrounded by an integral part of the plate positioned angularly to the plane of the panel. If this surrounding 90 part constitutes the edges of the plate then it would technically be called a "flange". However, it may be provided with a laterally extending part (or flange 28—27) so that the "surrounding part" would then 95 technically be called a "web". This laterally extending part is not an element of the broader claims of this application, therefore, to avoid the use of two different words to designate the same element, in different 100 claims, the word "web" is used to designate that part of the plate surrounding the panel and positioned at an angle thereto whether it constitutes the edges of the plate or not.

It has been proposed to press the central 105 portion of a metallic plate (or plates) so as to form a continuous web or flange surrounding a panel and to reinforce this panel by horizontal corrugations or other integral reinforcements which traverse the panel and 110

2
5 terminate adjacent the opposite portions of the web or flange. In such an arrangement the load upon the horizontal corrugations is transmitted to the continuous web or flange only through the intermediate means of the flat portion of the plate lying between the end of the horizontal corrugations and continuous web or flange. It has also been proposed to press the central portion of a metallic plate (or plates) so as to form a web or flange (supposedly) surrounding a panel and to reinforce this panel by horizontal corrugations or other integral reinforcements which are the same depth as the web 10 or flange where they merge into it. In such an arrangement the web or flange, as a beam, is destroyed. In my construction the transverse corrugations destroy only a part 15 of the value of the web, leaving a remaining portion which extends continuously around the panel to receive the stresses from the horizontal corrugations and to function as a beam and a stiffener. Such stresses are transmitted directly to the remaining portion 20 of the web.
25

That portion of the web between the corrugations serves as an excellent place for an attaching bolt or rivet because a bolt or rivet so positioned then also restrains the 30 corrugations against deflection. Furthermore, a bolt or rivet so positioned prevents the web from buckling as it has a tendency to do when acting as a beam.

In the drawings the usual parts of the 35 car are shown such as the end sill 1; end plate 2; side sill 3; side plate 4; side girth 5; corner post 6; side lining 7; side sheathing 8; end lining 9 and end fascia 10.

In my construction the central portion of 40 the metallic plate 11 (or plates 11-12) is pressed to form a continuous web 13-16 surrounding a panel 14. This panel 14 is reinforced with one set of corrugations 80-80 which springs from the panel 81 adjacent one portion of the web 82 and traverse 45 the major portion of the panel and then merges into the opposite portion 83 of the web. The panel is also reinforced by another set of corrugations 84-84 positioned vice versa to the first mentioned corrugations merging into the portions 82 of the web. These corrugations 80-84 may be positioned alternately with each other and preferably the two sets of corrugations 50 overlap each other. The remaining portion 26 of the continuous web extends continuously and uninterruptedly on three (or preferably four) sides of the wall. This web receives the load from the corrugations 60 and forms a beam or stiffener to prevent bulging in transmitting the load from the corrugations to the frame of the car. These remaining portions of the vertical parts 16 of the continuous web are prevented from 65 buckling or deflecting by being formed into

gral with the horizontal parts 13 of the continuous web (preferably by radial portions 17.) The web preferably lies against the adjacent frame member, such as corner post 6, end sill 1 or end plate 2 and is secured thereto by bolts 18 which are preferably positioned between the corrugations. Other means 19 are provided to secure the plate to the frame member which are preferably positioned in alignment with the corrugations. These two means may be used jointly or severally. The plate is secured to the end sill 1 by bolts 20-21 and to the end plate by bolts 22-23.

75 Figs. 9 and 10 show an enlarged section of the corner post and illustrates the relation of the web, the corrugations and the attaching bolts 18 and 19.

While I have shown and described the corrugations positioned horizontally, it is understood that the corrugations may extend vertically or otherwise, and still come within the scope of the invention, and furthermore, while I have described and claimed the wall made of "a plate", it is understood that it may be made of one or more united plates and still come within the scope of the invention.

This application is a continuation in part of my co-pending application Serial No. 30,778, filed May 16, 1925.

95 I claim:

1. A metallic plate pressed to form a continuous web surrounding a panel, said panel provided with corrugations which spring 100 from the panel adjacent one portion of the web and extend toward and merge into the opposite portions of said web, the corrugations which merge into one portion of the web are alternate with the corrugations 105 which merge into the opposite portion of the web.

2. A metallic plate pressed to form a continuous web surrounding a panel, said panel provided with corrugations which spring 110 from the panel adjacent one portion of the web and extend toward and merge into the opposite portions of said web, the corrugations which merge into one portion of the web overlap the corrugations which merge 115 into the opposite portion of the web.

3. A metallic plate pressed to form a continuous web surrounding a panel, said panel provided with corrugations which spring 120 from the panel adjacent one portion of the web and extend toward and merge into the opposite portions of said web, the corrugations which merge into one portion of the web overlap and are alternate with the corrugations 125 which merge into the opposite portion of the web.

4. A metallic plate pressed to form a continuous web surrounding a panel, said panel provided with corrugations which spring 130 from the panel adjacent one portion of the

web and extend toward and merge into the opposite portions of said web, being of less depth than the web where they merge into it, the corrugations which merge into one portion of the web overlap the corrugations which merge into the opposite portion of the web.

5. In combination with a frame member of a railway car, a metallic plate pressed to 10 form a panel portion with a continuous web having a flange, said panel provided with corrugations which spring from the panel adjacent one portion of the web and merge into the opposite portion of the web, said 15 panel provided with other corrugations which are positioned vice versa to the first mentioned corrugations, and means to secure said web to said frame member positioned between said first mentioned corrugations.

20 6. In combination with a frame member of a railway car, a metallic plate pressed to form a panel portion with a continuous web having a flange, said panel provided with corrugations which spring from the panel adjacent one portion of the web and merge 25 into the opposite portion of the web, said panel provided with other corrugations which are positioned vice versa to the first mentioned corrugations, and means to secure 30 said web to said frame member positioned between said first mentioned corrugations and aligned with said last mentioned corrugations.

7. In combination with a frame member of a railway car, a metallic plate pressed to 35 form a panel portion with a continuous web having a flange, said panel provided with corrugations which spring from the panel adjacent one portion of the web and merge 40 into the opposite portion of the web, said panel provided with other corrugations which are positioned vice versa to the first mentioned corrugations, means to secure 45 said web to said frame member positioned between said first mentioned corrugations, and separate means to secure said flange to said frame member positioned between the first mentioned means.

8. In combination with a frame member of a railway car, a metallic plate pressed to 50 form a panel portion with a continuous web having a flange, said panel provided with corrugations which spring from the panel adjacent one portion of the web and merge 55 into the opposite portion of the web, said panel provided with other corrugations which are positioned vice versa to the first mentioned corrugations, means to secure 60 said web to said frame member positioned between said first mentioned corrugations and aligned with said last mentioned corrugations, and separate means to secure said flange to said frame member positioned between the first mentioned means and aligned with the first mentioned corrugations.
